ELECTRIC HEATER

Howard L. Bourner, Nashville, Tenn., assignor to
Edwin L. Wiegand Company, Pittsburgh, Pa.

Filed Jan. 13, 1965, Ser. No. 83,414

Term of patent 14 years

(Cl. D81—10)

Fig. 1

Fig. 4

FIGURE 1 is a perspective view of the front of an electric heater, showing my new design,

FIGURES 2 and 3 are side and rear elevational views, respectively, and

FIGURE 4 is an enlarged fragmentary sectional view corresponding to the line 4—4 of FIGURE 1.

I claim:

The ornamental design for an electric heater, substantially as shown.
